EDWARD F. CHAFFEE, OF SYRACUSE, NEW YORK, ASSIGNOR TO THE O. M. EDWARDS COMPANY, INC., OF SYRACUSE, NEW YORK, A CORPORATION OF NEW YORK.

SPRING-BALANCE FOR WINDOW-SASHES.

1,383,982.

Specification of Letters Patent. Patented July 5, 1921.

Application filed October 27, 1916. Serial No. 128,036.

To all whom it may concern:

Be it known that I, EDWARD F. CHAFFEE, a citizen of the United States, and a resident of Syracuse, in the county of Onondaga and State of New York, have invented a certain new and useful Spring-Balance for Window-Sashes, of which the following is a specification.

This invention relates to spring balanced windows particularly applicable to railway cars, and has for its object a particularly simple, efficient, easily-accessible and durable construction of the means tending to move or raise the window sash in one direction; and the invention consists in the novel features and in the combinations and constructions hereinafter set forth and claimed.

In describing this invention, reference is had to the accompanying drawings in which like characters designate corresponding parts in all the views.

Figure 1 is a front elevation, partly broken away and partly in section, of a window embodying my invention.

Fig. 2 is a sectional view on line 2—2, Fig. 1.

Figs. 3 and 4 are cross-sectional views on lines 3—3, 4—4, Fig. 1.

This window construction comprises, generally, a frame, a sash movable in the frame and an extension spring connected to the sash to move the same in one direction as upwardly to counterbalance, overbalance or underbalance the sash. The extension spring in this embodiment of my invention, is a tension spring connected to each side of the sash. In some instances, compression springs may be used.

Preferably, the springs are arranged along the side edges of the sash.

1 designates the frame formed with the usual guideways 2 in which the window moves vertically.

3 is a stop forming one of the sides of each guideway 2.

4 is the sash having its margins movable in the guides 2, and 5 are tension springs extending along each margin of the window and connected at like ends to the sash and at their other ends to the frame.

Usually a portion of the frame, as each stop 3, is formed with a lengthwise recess therein and the spring 5 is arranged in the recess in each stop and connected at its

lower end to the sash and to its upper end 55 to the frame or the stop 3.

Each stop 3 is, in this form of my invention, shown as formed up from a strip of sheet metal bent to provide a lengthwise channel or recess 6 and an external lengthwise channel 7, the open side of the channel 7 facing outwardly in the direction of the general plane of the sash and being closed by the major part of the frame, and the channel 7 facing inwardly in a direction 60 parallel to the general plane of the sash, and serving as a curtain guide. The portion of the strip confining the recess 6 is rounding.

Each spring 5 is here shown as connected 70 at its lower end to an angular pin 8 extending from the face of the sash 4 into the recess of the stop through the open side 9, and at its upper end to a sash tightener 10 including a lever pivoted at 11 between its 75 ends to a suitable projection as an ear 12 on the window stops 3, the lever carrying at one end a roller 13 which bears against the window sash, and being connected at its other end at 14 to the upper end of the 80 spring 5. Although the spring may, if desired, be connected at its upper end directly to the frame. The stops 3 are detachably held in position in any suitable manner as by screws.

The sash is provided with the usual catches 21 which are shown as coacting with the window stops as the rounding part of the stop 3, or racks on the stops, and if desired the springs may be connected to movable parts of the catches 21 to exert force thereon in such direction as to hold the latches in their locked position. In operation, when the catches 21 are operated, the 85 springs tend to raise the sash.

This construction is particularly advantageous, in that the springs are readily accessible upon removal of the stops, as the springs are located in the stops in the construction shown in Figs. 1, 2, 3, 4.

What I claim is:

1. In a window construction, the combination of a frame, a sash movable in the frame, window stops each formed with a lengthwise recess, the sash extending behind the 105 stops and the recesses of the stops opening toward the portions of the sash behind the stops, and a spring extending lengthwise of

the recess of each stop and acting at one end against the window frame and at its other end against the sash, substantially as and for the purpose described.

- 5 2. In a window construction, the combination of a frame, a sash movable in the frame, a sash tightener carried by the frame, a spring extending along the side margin of the sash, and connected at one end to the

sash, and at its other end to the sash tightener, substantially as and for the purpose described.

In testimony whereof I have hereunto signed my name, at Syracuse, in the county of Onondaga, and State of New York, this 15 29th day of September, 1916.

EDWARD F. CHAFFEE.
